FUSE CUTTING AND SPLITTING AND CAP CRIMPING TOOL

Application filed October 7, 1930. Serial No. 486,988.

This invention relates to improvements in tools for the use of miners to cut and split fuses and to crimp the caps about the same as is necessary in the association of the fuses with the charges of powder used in blasting operations.

The principal operation of our invention is to provide a tool of this character which is very convenient and easy to manipulate while performing its several operations in a proper and clean-cut manner, and in which the cutting or main working element of the tool is readily removable from the body of the tool, so that it may be resharpened or replaced whenever necessary with but little trouble, and without having to discard the entire tool. Also this cutting element is mounted in connection with the body of the tool in such a manner that it is normally entirely concealed so that the sharp edges are protected from possible damage by contact with exterior objects.

A further object of the invention is to produce a simple and inexpensive device and yet one which will be exceedingly effective for the purpose for which it is designed.

These objects we accomplish by means of such structure and relative arrangement of parts as will fully appear by a perusal of the following specification and claims.

In the drawings similar characters of reference indicate corresponding parts in the several views:

Fig. 1 is a side elevation of our improved tool showing the cutting element retracted or in its normal position.

Fig. 2 is a side view taken from the opposite side of the tool with the cover plate of the body removed.

Fig. 3 is a fragmentary view similar to Fig. 2, but showing the cutting element fully advanced.

Fig. 4 is a longitudinal section taken on the line 4-4 of Fig. 1, but with the cutter in its advanced position.

Referring now more particularly to the characters of reference on the drawings, the body of the tool is of peculiar shape comprising an end member 1 and a straight extension 2 projecting from one end of the mem-

ber 1 intermediate the top and bottom thereof. A straight handle 3 is rigid with and depends from the bottom of the member 1 from the end of the same opposite the extension, and is preferably disposed at an obtuse included angle with the latter. The parts 1, 2, and 3 whether made of one or several pieces are arranged together to form a rigid unit.

Pivoted on the body member 1 and depending from the bottom of the same adjacent its end nearest the extension 2 is another handle 4, disposed in trigger-like arrangement relative to the handle 3 so that they may be both gripped by the same hand, with the handle 3 against the palm and the fingers against the handle 4 so that the latter may be pressed toward the handle 3. The upper portion of the handle 4 projects into a cavity 5 in the body 1 and at its upper end is forked to receive the adjacent end of the cutter bar 6 of the tool therebetween; this bar being flexibly pivoted to the handle by a removable pin P or the like. This bar extends lengthwise in the extension 2, being slidably mounted in a similarly shaped cavity 7 provided therein, and which of course communicates with the cavity 5. A compression spring 8 acts on the bar at its outer end to normally hold the same away from the corresponding end of the extension, and thus maintaining the handle 4 spread relative to the handle 3.

The body 1 is provided with a cylindrical passage 9 open to the top and extending down to communicate with the cavity 5 into which the adjacent portion of the bar 6 projects. This cavity is in direct transverse alignment with the bar so that the top of the bar forms a stop for the adjacent end of a length of fuse inserted into said passage; the diameter of the passage being sufficient to freely receive the fuse therein. Narrow slots 10 extend from the passage at the bottom to the ends of the body 1 above the plane of the extension 2.

Formed with and projecting upwardly from the bar 6 at its handle end is a relatively thin blade 11 whose cutting edge is vertically disposed and faces the opposite end of the bar. The blade is normally disposed

beyond the passage 9 so as not to interfere with the insertion of a fuse to the bottom of the passage or until it engages the top of said bar.

- 5 Adjacent the body portion 1 the extension 2 is provided with a transverse slot 12 for its full width and which extends downwardly from the top to a termination intermediate the top and bottom of the bar 6 and of course 10 communicating with the cavity 7. The rear edge of this slot on one side of the cavity and toward the bottom is concavely rounded and is sharpened as at 13 with a taper extending outwardly toward the outer end of the extension, as indicated in Figs. 1 and 4. The bar 6 is provided with a similar slot 14 extending from its top downwardly and normally registering with the slot 12. The forward edge of the slot 14 on the side adjacent 15 the sharpened edge 13 is also concavely curved and sharpened as at 15, with a taper toward the opposite side of the bar. The edges 13 and 15 therefore form cooperating cutting elements when the bar is moved lengthwise 20 relative to the body.

Further along on the extension the same is provided with another transverse slot 16 similar to the slot 12. This slot 16 is formed on one side toward the bottom and on its 25 rear end with a semi-circular concave curvature 17, which is bluntly sharpened as indicated in Fig. 4. The bar 6 also has an additional slot 18 to normally register with the slot 16 and having a semi-circular concave 30 curvature as at 19 on its forward edge which is also bluntly sharpened, to cooperate with the edge 17. It may here be noted that in the above description the term "forward" denotes the ends of the slot nearest the body 35 member 1, while the term "rear" of course denotes the opposite ends of the slots. The above parts are so arranged that when the bar is fully advanced by the movement of the handle 4 toward the handle 3, the relatively 40 fixed and movable cutting edges 13 and 15 of the body and bar respectively completely overlap each other, as shown in Fig. 4. A fuse initially inserted in place in the slots 12 and 14 so as to extend across the body will 45 therefore be completely and cleanly cut through. The relatively fixed and movable edges 17 and 19 of the bar and body however do not overlap each other but merely cooperate to form a complete circular outline with 50 the slots 16 closed by the bar as shown in Fig. 3. Said cooperating edges then form crimping elements, the diameter of the opening thus formed relative to that of the fuse cap being sufficient to pat the desired crimp 55 in the cap all around the same.

At the same time the cutting edge of the blade 11 is moved completely across the passage 9 diametrically of the same, so as to split through the corresponding portion of a length 60 of fuse inserted in said passage. The slots 10

allow said passage to be readily cleared of any powder which may lodge in the same or on the bar with the splitting operation. Owing to the position of the passage 9, and the slots through which the fuse is initially engaged with the tool, relative to the handles, the tool may be held in a convenient position in the hands so as to be readily and easily engaged with the fuse whether the same depends vertically or is horizontally disposed. 70 All the various cutting edges on the movable bar being normally concealed and protected, they are not apt to become nicked or otherwise damaged by contact with any exterior objects. 75

The body has above been described as being one piece, but for convenience of manufacture and to enable the blade to be readily disconnected from the handle, said body is formed and provided on one side with a removable cover plate C, whose removal exposes one side of the cavities 5 and 7 and of course exposes the cutting bar also. 80

It is customary to form a circular cavity in the cartridge to be fired for the insertion of the fuse therein. This is usually done by inserting a rod or similar implement into the cartridge the necessary distance. With the use of a make-shift tool for the purpose, and which is usually steel or iron, a certain element of danger enters into the operation, especially if the metal has any more or less sharp corners or is at all rough. We have therefore provided a convenient tool for the above purpose, incorporated with the fuse cutting tool, which obviates all danger in its use. Such tool comprises a circular smooth-pointed member 20, of copper or other relatively soft metal which is formed as a part of the handle 3 on its lower end, the body and other members of the tool being necessarily steel or other hard metal in order for the tool to have the necessary rigidity and wearing qualities. 95

From the foregoing description it will be readily seen that we have produced such a device as substantially fulfills the objects of the invention, as set forth herein. 100

While this specification sets forth in detail the present and preferred construction of the device, still in practice such deviations from such detail may be resorted to as do not form a departure from the spirit of the invention, as defined by the appended claims. 115

Having thus described our invention what we claim as new and useful and desire to secure by Letters Patent is:

1. A tool of the character described comprising a body consisting of an end portion and a horizontal extension projecting from one end of the same, a handle depending from and rigid with the end portion, communicating cavities formed in said end portion and extension, a cutter bar slidable in said extension cavity and projecting into the end por- 125

tion cavity, another handle pivoted on the end portion of the body in cooperating relationship with the first named handle and extending into the corresponding cavity for pivotal connection with the adjacent end of the bar, said bar and extension intermediate their ends having normally registering transverse slots open to the top of the extension and bar; the opposite ends of the slots of the bar and extension respectively and on one side being sharpened to form cooperating cutting elements.

2. In a tool of the character described, a hollow body member, a bar slidably mounted in said member, said bar and member having transverse slots open on the top of the same and of sufficient width and depth to receive the cross sectional area of a fuse therein, cooperating cutting edges formed on adjacent sides of the bar and body member at the opposite ends of the corresponding slots, and hand means applied to the bar for moving the same lengthwise in the body member.

3. In a tool of the character described, a hollow body member, a bar slidably mounted in said member, said bar and member having transverse slots open on the top of the same and of sufficient width and depth to receive the cross sectional area of a fuse therein, cooperating cutting edges formed on adjacent sides of the bar and body member at the opposite ends of the corresponding slots toward the bottom thereof, means acting on the bar to normally maintain the slots in alinement whereby the cutting edges are separated, a handle rigid with the body member depending from the same at one end, and another handle connected to the adjacent end of the bar and pivoted on the body member, said last named handle depending in cooperating relationship to the rigid handle.

4. A structure as in claim 2, in which the cutting edge of the bar-slot is normally disposed inwardly of the adjacent end of the slot of the body member, whereby said edge is protected against damaging contact with exterior objects.

5. A structure as in claim 2, in which the body member, beyond the slot, is provided with a circular passage open to the top and depending to the upper surface of the bar, and a blade projecting upwardly from said bar to move diametrically across the passage over a certain portion of the length thereof, with the longitudinal movement of the bar, said blade being normally clear of the passage.

6. In a fuse splitting tool, a body member having a circular fuse-receiving passage extending downwardly from the top, a bar slidably mounted in the body below and in the plane of the passage whereby to form a stop for a length of fuse inserted in said passage, a blade on and upstanding from the bar and movable across the passage to split the fuse

for a portion of its length, means acting on the bar to normally hold the blade beyond one side of the passage, and hand means for sliding the bar lengthwise to cause the blade to move across the passage.

7. A structure as in claim 2, in which one side of the body is formed as a removable plate whose removal exposes the bar, and said bar is removably connected to said bar moving means.

In testimony whereof we affix our signatures.

JOSEPH S. CADEMARTORI.
WALLACE S. DRAPER.
